UNITED STATES PATENT OFFICE.

LOUIS J. REMMEL, OF NEWARK, NEW JERSEY.

ROTARY BROOM OR BRUSH.

1,309,695.

Specification of Letters Patent. Patented July 15, 1919.

Application filed September 26, 1918. Serial No. 255,775.

To all whom it may concern:

Be it known that I, LOUIS J. REMMEL, a citizen of the United States, and a resident of Newark, county of Essex, and State 5 of New Jersey, have invented certain new and useful Improvements in Rotary Brooms or Brushes, of which the following is a specification.

My invention relates to rotary brooms or 10 brushes and more particularly to brooms or brushes used for street sweeping, track cleaning and the like.

The present invention is an improvement 15 on my earlier Patent No. 743,195, granted Nov. 3, 1903.

An object of the present invention is to 20 provide a brush of the type referred to which is simple and can be cheaply constructed and wherein the brush material and retaining members are easily removed so as to provide for the easy and convenient 25 replacement of brush material, such as reeds, ratan or the like, by simple removal of the brush holding members without taking the brush apart.

Another object of the invention is the 30 provision of stay or reinforcing members within the fold of the brush material which are likewise removable and which serve to impart stiffness to the brush material and to separate and hold the tufts or folds thereof in proper relative position.

Other objects of the invention will appear 35 in connection with the following description, and with the foregoing and related objects in view, my invention consists in the elements, parts, features of construction and combinations herein set forth and claimed.

In the drawing forming part of this specification I have shown one form of brush in 40 which my invention may be embodied.

In said drawing, Figure 1 is a perspective view of one half of a brush head. Fig. 2 is a longitudinal sectional view taken substantially on the broken line 2--2, Fig. 1. Fig. 45 3 is an end view of a completed brush, and Fig. 4 is a fragmentary perspective view showing the relation of the holding bar and the stay bar to the brush material.

The brush body preferably comprises a 50 series of disk-like members of substantially skeleton form which are spaced apart, and aligned openings therein are provided, with lengthwise extending members therein connecting the skeleton-like disk members to

form substantially a cylindrical brush body. The disk members may conveniently be made in halves and bolted together, with preferably square central openings formed between them to embrace blocks on the brush 60 shaft.

For a sweeper brush of four feet in length, or thereabout, there may be three different types of disks; an end disk or head 10, an intermediate disk 11, preferably 65 placed midway between the heads 10 and 12, and spacing disks 13. The disks 10, 11 and 12 may be provided with slots 14 for the reception of back boards 14^a which serve to prevent the brush material 15 being pushed 70 or forced inwardly to an undue extent, and all the disks 10, 11, 12 and 13 have aligned openings 16 for the reception of preferably wooden bars 17 which are preferably secured tightly in place when the brush halves 75 are constructed and which cannot be removed as the wood swells quickly upon being exposed to moisture in use. The bars 17 may be secured in place in any desired way, however, and serve as separators for the 80 sections of brush material.

An important feature of the present invention resides in lengthwise removal of the brush material holding members, which may be in the form of rods or tubes 18. Such 85 members have a sliding fit in the aligned openings 19 arranged in all the disks and spaced substantially midway between the separator bars 17. Removable means for fastening the brush holding members 18 in 90 place are provided, as, for example, cotter pins 20 may be inserted through openings 21 in sleeves 22 on the headers 10 and 12, providing extensions of the openings 19 therein, and in holes 23 provided in the rods, 95 bars, tubes or the like 18. These brush material retaining members are made of metal, as iron or steel bars or pipe and, having a sliding fit in the openings provided therefor, may be readily removed by direct longitudinal movement. Where wood or other similar material is used for brush retaining means, it swells quickly upon exposure to the weather in the severe use to which these brushes are put, and cannot be subsequently 100 removed. Ordinarily it is sufficient to secure the brush material holding members in place at one or two points only, and it is sufficient to provide the heads 10 and 12 with the sleeves 22 and cotter pins 20, and such 105 110

sleeves need not be provided either on the intermediate disks 11 or the spacing disks 13.

Adjacent to the retaining members 18, and between the folds of the brush material 15, I provide stay or stiffener bars 24 which may be of wood but in such case are of sufficiently reduced cross-section to be readily inserted and removed longitudinally from the alined openings provided for their reception in the several disks. Means are preferably provided for preventing their unintentional or premature withdrawal, as, for example, nails 25 may be driven therein adjacent to the disks through which they pass, and may be pulled out when the stay bars are to be removed. The stay bars 24, placed radially outside of the retaining members 18, are preferably somewhat wider than said members 18. They hold the folds of the folded over brush material apart at a proper distance and also, acting in conjunction with the separator bars 17, serve to keep the separate projecting tufts or rows of reeds, ratan or other brush material properly spaced from one another all the way around the brush. With the outer faces of the separator bars 17 and stay bars 24 arranged at substantially the same distance from the brush axis, as shown, the brush material is held up substantially stiffly and strongly to its work on both sides and with substantially equal tension or resisting power in both directions. By making the brush material retaining members of metal, as tubing, and the separate stay bars of wood, great strength is obtained without unnecessarily great weight.

To put brush material in place in the brush it is only necessary to forcibly insert 40 the folded new brush material in place between the separator bars 17, whereupon the holding members 18 may be inserted through the openings 19 provided therefor and passed through within the fold of the brush material and locked in place as by means of the cotter pins 20. Then the stay bars 24 may be introduced in a similar manner. The same steps are performed in repairing worn brushes, but in such case it is, of course, necessary to first free and withdraw the stay bars and the rods or tubes 18, which can be done by direct longitudinal movement. The old or worn brush material may then be readily removed and replaced by new material. With the brush constructed as described, the filling operations may be advantageously carried out in a suitable filling machine, by means of which the folded over reeds are forcibly pushed into place 55 between the bars 17, 17 and held while the bars 18 are put in place. While filling may be done by hand, if desired, it is a feature of great convenience and practical advantage to have the brush of such construction 60 as to be well adapted for machine filling,

and various other advantages are secured by my improved construction, as will appear from the foregoing.

I claim:

1. In a rotary brush, a skeleton frame 70 comprising a plurality of substantially parallel circular disk members spaced apart and made up of part circular members removably secured together, lengthwise extending bars connecting said disks and forming separators for brush material, folded over brush material between said separator bars, and endwise removable brush material holding means inserted through alined openings in the disks and passing through within the 75 folded over parts of the brush material.

2. In a rotary brush, a skeleton frame comprising a plurality of substantially parallel circular disk members spaced apart and made up of part circular members removably secured together, lengthwise extending bars connecting said disks and forming separators for brush material, folded over brush material between said separator bars, endwise removable brush material holding 85 means inserted through alined openings in the disks and passing through within the folded over parts of the brush material, and stay bars arranged between the folds of brush material.

3. In a rotary brush, a skeleton frame comprising a plurality of substantially parallel circular disk members spaced apart and made up of part circular members removably secured together, lengthwise extending bars connecting said disks and forming separators for brush material, folded over brush material between said separator bars, endwise removable brush material holding 90 means inserted through alined openings in the disks and passing through within the folded over parts of the brush material, and stay bars arranged between the folds of brush material.

4. In a rotary brush, a skeleton frame comprising a plurality of substantially parallel circular disk members spaced apart and made up of part circular members removably secured together, lengthwise ex-

100 tending bars connecting said disks and forming separators for brush material, folded over brush material between said separator bars, endwise removable brush material holding means inserted through alined openings in the disks and passing through within the folded over parts of the brush material, and stay bars arranged between the folds of brush material, the stay bars being wider than the brush holding members and their outer faces being at substantially the same distance from the brush axis as the outer faces of the separator bars.

4. In a rotary brush for street cleaners and the like, a skeleton brush body comprising a series of parallelly arranged, spaced apart circular disks made up of part circular members removably secured together, longitudinally arranged separator bars passing through alined openings provided therefor 110 in said disks and serving as separators for brush material and to hold the disks in place relative to one another, a series of boards extending longitudinally of said brush body at substantially the interior thereof and 115 serving to prevent undue inward movement of the brush material, folded over brush material between said separator bars, and longitudinally extending metallic brush retaining means passing through alined openings 120

provided therefor in the disks of the brush body arranged substantially midway between such separator bars and passing within the folded over portions of the brush material, sleeves on the end disks of the brush head providing extensions of the openings for the brush retaining members therein, and cotter pins passing through openings

provided in such sleeves and in said brush retaining members for releasably holding 10 said brush retaining means against longitudinal movement.

In testimony that I claim the foregoing, I hereto set my hand, this 20 day of September, 1918.

LOUIS J. REMMELE.
